MATCH PACKET

Rodney S. Pullen, Akron, Ohio, assignor to
 Pullenlite Company, Philadelphia, Pa., a corporation of Pennsylvania

Application July 13, 1933, Serial No. 680,248

6 Claims. (Cl. 206—29)

The invention relates to a match packet in which the matches are automatically ignited by longitudinal withdrawal and the matches thread spaced rows of perforations of a wrap that folds lengthwise of the matches.

In this type of match packet a short flap adjacent one row of perforations folds down against the exposed match portions intermediate the threaded rows, a paper bale transversely folds about and encases the inner wrap portions intermediate the rows on opposite sides of the matches, and a long flap adjacent the other row of perforations folds down over the bale, thence around the edge of the folded bale and up against the bale portion on the other side of the packet.

A purpose of the invention is to provide a novel packet of the character indicated adapted to easy and inexpensive manufacture and well suited to the needs of service.

20 A further purpose is at once to secure a straighter packet and to prevent a stitch holding the bale to place upon the inner wrap portions from binding the central matches of the row of matches of a packet of the character indicated, 25 securing this result by clinching the stitch ends outwardly as distinguished from clinching these ends inwardly.

A further purpose is more tightly to seal from the air the portion of the packet forming a common compartment for the match heads by gluing the edges of the paper bale to the outer wrap portion.

30 A further purpose is to provide a packet of the character indicated with a better grip at its sides and to strengthen it against bulging or bending with resultant lessening of the seal of the packet interior during use if a user grips the packet at its edges, as for match removal, by insetting the side portions of the paper bale from the side portions of the wrap.

A further purpose is to reduce the speed of ignition during match withdrawal from a packet of the character indicated by limiting the ignition material to one side only of the match row.

45 A further purpose is to taper the inner portions of the wrap at the sides and toward the match heads so that the bale and partially folded packet can be assembled by slipping the preformed bale over the match head end of the partially folded 50 packet.

Further purposes will appear in the specification and in the claims.

I have elected to show one main form only of the different forms of my invention, showing 55 however a minor modification and selecting a

main form and a modification thereof that are practical and efficient in operation and which well illustrate the principles involved.

Figures 1 and 2 are front and rear perspective views, partly broken and illustrating a desirable form of my invention.

Figure 3 is a front perspective view showing a somewhat different form.

Figures 4 and 5 show in plans respectively an unfolded wrap and an unfolded bale.

Figure 6 is an end elevation of a folded bale, ready to assemble with a partially folded packet.

Figure 7 is a plan view showing the partially folded packet, tapering at the sides toward the match heads and about to receive the preformed bale.

Figures 8, 9 and 10 are side elevations showing a partially wrapped packet in successive stages of folding.

Figures 11, 12 and 13 are front elevations of the structures of Figures 8, 9 and 10 respectively.

Figures 14, 15 and 16 are side elevations showing further stages of manufacture.

Like numerals refer to like parts in all figures.

Describing in illustration and not in limitation and referring to the drawings.

A packet of this type includes broadly matches threading perforations arranged in spaced transverse rows within a long wrap, having inner folds against the exposed match portions intermediate the rows, a paper bale covering the match head ends and the inner folds of the wrap, and the outer folds of the wrap covering the bale.

The match portions inwardly of the projecting stick ends may thus be considered as inside a double casing or double compartment, of which the divisions may be respectively designated the match ignition compartment being formed by the inner folds of the long flap closed at the sides and by the side portions of the bale, and the walls of the match head compartment being formed by a downwardly projecting perforated inner portion of the main wrap, by the bale closed across the heads, and by the bottom outer fold of the wrap.

As thus described this structure is shown and described in applicant's prior applications and patents, the present invention being directed to novel details thereof that include a new stitch fastening of the assembled members of the packet, insetting the lateral walls of the head and ignition compartments (formed by the side portions of the bale) from the side edges of the packet, as determined by the side edges of the outer folds of the wrap, a lateral tapering of the inner folds of the wrap for more easy assembly with the

folded bale, a glue seal between the bottom edges of the folded bale and the bottom fold of the wrap and preferable limitation of ignition material to one side only of the packet.

5 The wrap 19 may suitably be made up of flaps 20, 21, 22 and 23 spaced by end portions 24, 25 and 26 of which the interior end portions 24 and 25 are apertured at 27 and 28. There are seven transverse scorings at 29, 29', 30, 30', 31, 31' 10 and 32.

I provide the blank with a usual coating of ignition material in position to be frictionally engaged by the match head during match withdrawal but may limit this coating to one inner 15 face only of the ignition chamber, as along a transverse strip at either 33 or 34 but not necessarily at both strips. In fact, a one side "striking" of the matches, as distinguished from the usual two side striking thereof, may be even the more 20 desirable in order to give an advantageously more slowly flaming during ignition.

The bale 35 which forms the sides of both ignition and match head compartments of the finished packet, as well as the front and back walls of the head compartment, suitably comprises a rectangular blank bent along score lines 36, 37, 38 and 39 from the flat contour of Figure 5 to the rectangular contour of Figure 6. The score lines are shown as double score lines.

25 I set the side portions 40 and 41 of the bale inwardly in the finished packet from the side edges of the wrap, and to secure this result, cut the blank of the wrap with inward offsets at 42 and 43 and also for more easy manufacture 30 preferably provide the sides of the wrap portions 20 and 21 intermediate the score lines 29' and 30 and score line 29 to the end of the wrap, with a relative taper toward the score lines 29 and 29'. This permits the preformed bale easily to be slid over the partially folded packet, as indicated in Figure 7.

35 The matches and wrap may be assembled in the usual way to the stage of Figures 9 and 12, during which period the bale is bent to its form as indicated in Figure 6; after which the packet structure of Figure 9 and the bale structure of Figure 6 are brought to transverse registry and moved relatively into assembly position, the forward taper at 44 of the wrap facilitating assembly to the position of Figure 10.

40 In Figure 10 the bale and package structures have been brought together from their position of Figure 7, and are about to be fastened together by a stitch 45, involving another feature of the invention.

The stitch spans between its tines a plurality of the intermediate matches and after insertion has its tines clinched at 46 outwardly as distinguished from inwardly.

45 I usually prefer to make each packet include ten matches and in this event suitably locate the stitch centrally of the packet, to include four matches between its tines with three matches on each side outside of the stitch.

48 The outward clinching of the tines avoids having the clinched tine ends come directly opposite the body portion of the stitch inside of the tines by which the matches under the tines would be bound objectionably. It also offers a better support of the packet portion outside the tines.

53 The tines cooperate with the bodies of the stitches to give a cantilever spring pressure to the adjoining outside matches with reactive spring pressure against the intervening matches. The package is thus improved and danger of

the pressure of the stitch tines pulling heads from the matches during withdrawal is reduced.

58 After stitching the long flap is turned down from the position of Figure 10 to that of Figure 14 and thence down around the head end 80 of the packet to the position of Figure 15, where it may be held to place by glue suitably applied to the blank before assembly, as at strips 47.

85 Another feature of the invention includes a glue seal around the lower edges of the match head compartment, between the bottom strip 48 of the wrap and the adjacent edges of the bale.

90 I prefer to coat with glue the head and (bottom) strip 48 of the blank at 49, between the lines 31 and 31' and after assembly of the packet to the stage of Figure 15 press the wrap and bale into gluing contact along the lower edge of the bale, by a suitable roll or other means 50.

95 It is evident that the gluing of the edges of the bale to the wrap wall across the head compartment forms convenient tight attachment of the bale walls to the wrap and makes a tighter air seal of this head compartment than would otherwise be feasible; but that very much of the advantage of this tight sealing would be secured 100 by gluing the sides of the bale near their edges to the wrap wall near the end of the compartment.

105 The tightness of seal of the head compartment against leakage of air into it is of importance in reducing (smothering) the flame from accidental ignition of a match head or heads within the compartment and thus reduces the injury from any such accidental ignition. The seal is most effective when the edges of the bale, as at 110 51, are glued to the end of the compartment, but nearly as good results can be secured by gluing the sides of the bale near the edges as at 52 to the sides of the wrap. I prefer the gluing of the edges both because it is more reliably effective 115 and because there is less difficulty in preliminary handling of the glued wrap or glued bale (which ever one is selected to be glued) or in applying the glue just before their attachment.

120 I usually prefer to have the front and back faces of the finished packet free for advertising matter and locate the metal stitch therefore underneath the outer folds of the wrap.

125 There are some advantages however in placing the stitch through the whole packet, and sometimes this may be preferable in that it eliminates or lessens the need for gluing.

130 I have illustrated this in Figure 3, the structure in this figure being optionally exactly as already described except that the stitch goes through the entire packet instead of through that portion merely of the packet that is inside the outer folds of the wrap.

135 In view of my invention and disclosure, variations and modifications to meet individual whim or particular need will doubtless become evident to others skilled in the art, to obtain all or part of the benefits of my invention without copying the structure shown, and I, therefore, claim all such in so far as they fall within the reasonable spirit and scope of my invention.

140 Having thus described my invention, what I claim as new and desire to secure by Letters Patent is:

145 1. In a match packet of the type which ignites the match during withdrawal, a wrap folded upon itself longitudinally of the matches to form a cover and having individual openings through which the matches extend and a metal stitch whose length is transverse to the matches, which 150

passes through the packet at the ends from side to side between the match sticks and whose ends are turned outwardly, away from each other.	4. A match packet of the type that ignites during withdrawal and a metal stitch holding the side walls together, passing between and transversely across the matches and turned outwardly at its ends.	80
2. A match packet of the type which ignites on withdrawal and comprising a wrap extending longitudinally of the matches about the matches and having individual openings for the matches, a bale extending about the packet laterally and having its ends near to each other on one side of the packet and a stitch extending through both sides of the bale between the matches and through the wrap and whose ends are turned outwardly away from each other.	5. A match packet having wrap walls tapered in both directions from a section transverse to the matches and which has individual openings for the match sticks, toward the match heads, the tapered portion being throughout its full length of less width than the rest of the wrap, and a bale enclosing the lateral edges of the wrap at the tapered portion.	85
3. A match packet of the type which ignites on withdrawal and comprising a wrap extending longitudinally of the matches about the matches and having individual openings for the matches, a bale extending about the packet laterally, a stitch extending through both sides of the bale between the matches and through the wrap and whose ends are turned outwardly away from each other, the wrap being continued about the stitched part of the package to cover both sides of the stitch and extend about the heads of the matches,	6. In a match packet having wrap walls tapered in both directions from a section transverse to the match and which has individual openings for the match sticks, toward the match heads, the tapered portion being throughout its full length of less width than the rest of the wrap, a bale enclosing the lateral edges of the wrap at the tapered portion and an outer wrap covering surrounding the bale.	90
28 and means for holding the outer parts of the wrap in place.	RODNEY S. PULLEN.	100
